United States Patent Office

Des. 198,119
Patented May 5, 1964

198,119

SIGN OR SIMILAR ARTICLE

Austin P. Winters, 121 Ashland Road, Summit, N.J.

Filed Oct. 8, 1963, Ser. No. 76,904

Term of patent 14 years

(Cl. D1—12)

FIG. 1

FIG. 2

FIG. 3

FIG. 4

FIGURE 1 is a front elevation of a sign or similar article, showing my new design;

The broken line representation of letters and an arrow in FIG. 1 are for purposes of illustration only.

I claim:

The ornamental design for a sign or similar article, as shown and described.
